BURNER SAFETY CONTROL DEVICE

John L. Harris, Whitefish Bay, Wis., assignor to
 Perfex Corporation, Milwaukee, Wis., a corporation of Wisconsin

Application December 28, 1946, Serial No. 719,100

22 Claims. (Cl. 158—28)

1

This invention relates generally to temperature control systems and apparatus, and more particularly to a system and apparatus for controlling the various operating cycles of a space heating furnace using oil or other fluid as a fuel.

In general, a combustible mixture of oil or other suitable fluid fuel and air (hereinafter referred to as "fuel") is introduced into the combustion chamber of a furnace through a suitable apparatus which usually includes, in the case of oil, a motor-driven pump and blower, hereinafter referred to as a "burner" or "fuel supplying means." The burner delivers the oil into the furnace in finely divided particles forming a readily ignitable mixture. Placed near the burner is some means for igniting the combustible mixture discharged therefrom, hereinafter referred to as an "igniter." The igniter may consist of a wire which upon passage of electric current therethrough is heated to the ignition temperature of the fuel. It will be readily understood that ignition must take place simultaneously with, or at least very shortly after, the introduction of the fuel into the combustion chamber of the furnace. To delay ignition would allow too great a concentration of fuel to build up in the combustion chamber, which, when ignition did finally occur, might explode, causing considerable damage. After initial ignition has taken place, the igniter has served its purpose and may thereupon be made inoperative. With the burner delivering fuel to the furnace and the fuel burning at the desired rate, if for some unforeseen reason, such as failure of air supply to the burner or momentary fuel stoppage, combustion should cease, hereinafter referred to as "flame failure," further operation of the burner would cause the furnace combustion chamber to be filled with unburned fuel in such a concentration as to present a highly dangerous explosion hazard. In order, therefore, for a space or room to be properly and safely heated by a fluid fuel burning furnace, a room thermostat, a thermostat responding to the temperature of combustion, the burner, and an igniter must be so interconnected as to cause the burner and igniter to operate in proper sequence and to shut down when explosion danger exists. Under some conditions it is desirable that the control device which so interconnects the above mentioned elements should shut off the burner upon ignition failure, should shut off the burner on flame failure, then automatically recycle, placing the furnace back in operation shortly thereafter, and if upon recycling, proper combustion still does not occur, should move to a position preventing further recycling (this position is hereinafter referred to as "safety shut down"). It has proved

2

advantageous to also provide a resetting mechanism, manually actuated, for resetting the control device after a safety shut down, permitting the furnace to be placed back in operation after corrective repairs have been made. Experience has shown that janitors or personnel attending such heating systems as herein described often tie down the resetting mechanism in reset position and thus by-pass the safety mechanism in the control device. The resetting mechanism therefore should be so constructed as to prevent the furnace from operating while the resetting mechanism is in actuated or reset position.

The primary object of this invention is to provide a control system incorporating parts constructed and combined in a novel manner affording a simplified, compact, and durable mechanism for safely and efficiently operating a fuel burning heating apparatus.

Another object of this invention is to provide a control device with an improved manual reset mechanism for placing the furnace back in operation after safety shutdown, but effectively preventing the furnace from operating as long as the reset mechanism is in actuated or reset position.

Another object of this invention is to provide a control device incorporating means for limiting the period during which the igniter is at or above the fuel combustion temperature.

Another object of this invention is to provide a control system incorporating parts constructed and combined in a manner affording timed operation of an ignition means, recycling in the event of a power or flame failure, and safety shutdown through the medium of a single combustion responsive element and of a single heater actuated warp element.

More particularly, the present invention contemplates and has as a further object the provision of a control mechanism incorporating a relay controlled switch positionable to initiate combustion in response to a demand for heat and to terminate combustion when the demand for heat is satisfied, a single combustion responsive element, a single heater actuated warp element, and a manual reset member constructed and combined in a manner affording timed operation of an ignition means, recycling in the event of a power or flame failure, and safety shut down in the event combustion is not initiated or fails during normal operation prior to satisfaction of a demand for heat and in a manner such that so long as the reset member is held in its actuated resetting position, the relay is incapable of positioning the switch controlled thereby to initiate combustion. In addition, it is also contemplated

that the parts be so constructed and combined that once the relay is positioned to initiate combustion, an actuation of the manual reset mechanism will not effect a termination of such operation.

The construction, application and operation of mechanism embodying the present invention will become readily apparent as the disclosure progresses and particularly points out additional objects and features considered of special importance. And accordingly this invention may be considered as comprising a system and/or mechanism, combinations and sub-combinations incorporating parts constructed and combined as hereinafter more fully set forth in the description and appended claims, reference being had to the accompanying drawing illustrating but one embodiment of the invention and in which:

Fig. 1 is a perspective rear view of a portion of the control device embodying the invention, with a portion of the casing cut away to better show the arrangement of parts mounted therein, the parts being shown in the positions assumed when a demand for heat is satisfied;

Fig. 2 is a view similar to Fig. 1 showing the parts in the positions assumed during normal operation in response to a demand for heat;

Fig. 3 is a view similar to Fig. 1 showing the parts in the positions assumed immediately following a flame failure, but prior to deenergization of the relay and consequent opening of the relay contacts;

Fig. 4 is a view similar to Fig. 1 showing the parts in safety shut-down position;

Fig. 5 is a perspective front view of the control device with the front cover removed;

Fig. 6 is a view similar to Fig. 5 with the front cover in place;

Fig. 7 is a sectional view taken generally along line VII-VII of Fig. 6 with all parts except those relating to the combustion responsive element removed and with a rearwardly extending tubular piece only partially in section;

Fig. 8 is an enlarged detailed view of a slip friction connection between a combustion responsive element and a notched arm whose relative position within the control device is best shown in Figs. 1 to 4;

Fig. 9 is a sectional view taken generally along line IX-IX of Fig. 6 with the base plate and all parts, except those relating to the reset mechanism, removed;

Fig. 10 is a view similar to Fig. 9, but with the reset mechanism in actuated or reset position; and

Fig. 11 is a schematic wiring diagram of a temperature control system utilizing the control device shown in Figs. 1 to 4.

Referring now to Fig. 1, in which is shown a casing 10 with two outwardly extending mounting lugs 11 and 12, the inner side of the front wall of casing 10 is partially covered by a plate 13 detachably fastened thereto, as will be described subsequently with reference to Fig. 5. Plate 13 is made of any suitable electrical insulating material and extends into an opening 14 in the side of the casing 10. An irregularly shaped bracket comprising a base portion 15 is secured in abutting relation to plate 13 in any suitable manner and is provided with two inwardly extending vertically spaced portions 17 and 18. Portion 18 is provided with an internally threaded hole therethrough receiving an adjustable stop member 19. Portion 17 mounts an inwardly projecting extension 20 to which is attached one end 75

of a spring 21. The other end of the spring 21 is fastened to the adjacent end of a plate 23 having a pair of opposed parallel ears 24 (only one of which is shown) provided with aligned holes through which extends a rigid pin 25 having one end fixedly supportedly mounted on bracket base 15 in any suitable manner. The holes in the ears 24 and pin 25 provide a pivot mounting for plate 23 which is biased in a counter-clockwise direction by the action of spring 21. Two U-shaped temperature responsive members 26 and 27, having legs 28, 29 and 30, 31 respectively, are secured to the free end of the plate 23 in spaced generally parallel relation with respect to each other by means of rivets 32 which pass through aligned openings in the lower end portions of legs 28, 31 and plate 23, and through spacers interposed between the legs and the plate. Leg 31 of temperature responsive member 27 rests against the adjustable stop 19. Riveted to the temperature responsive member 26 is a U-shaped bracket 34 enclosing an electric heating element 35. A strip 36 and a resilient blade 37, carrying a contact 38, are secured to opposite sides of the free end portion of leg 28 by means of rivets and clamping bar 39. A pin 40 of electrical insulating material has an enlarged end portion thereof pivotally mounted in any suitable manner to the back side of strip 36.

Secured by any suitable means to the plate 13 is a rectangularly shaped bracket 41 having inwardly extending portions 42, 43, 44, and 45. Portion 44 is provided with an internally threaded hole mounting a threaded member 46 constituting a stationary contact opposing movable contact 38. Portion 44 also mounts a permanent magnet 48 positioned in opposed relation to the enlarged free end portion of strip 46 which functions as an armature for magnet 48. A terminal lug 49 extends through a rectangular opening in the base of the bracket 41 and is electrically connected to the extending portion 43 by a conductor 50. Portion 42 has an internally threaded hole therethrough mounting a threaded contact member 51. A block 52 of electric insulating material is secured in any suitable manner to extending portion 45 and mounts a plate 53 in spaced insulated relation with respect to portion 45. An L-shaped bracket 54 is fastened to the plate 53 by means of screws 55. The upwardly extending portion of this bracket mounts a rectangularly shaped resilient hinge member 56 which extends upwardly therefrom. Secured to the upper or free end of hinge member 56, as by means of rivets and a clamping pad, is an upwardly extending bar 58 having an opening therethrough loosely receiving pin 40. The free end of pin 40 is provided with cap 59 and a spring 60 surrounds an intermediate portion in opposed relation to bar 58 and the enlarged end of the pin so as to serve as a lost motion connection between the bar 58 and the temperature responsive member 28. Bar 58 is provided with an internally threaded hole therethrough near the free end thereof which mounts a threaded contact member 61. A generally rectangular mounting plate 62 is fixedly secured in any suitable manner to plate 13 and is provided with off-set portions 63, 64, and 65, one of which, 63, is electrically connected by conductor 67 to a terminal lug 68 projecting through an opening in the plate 62. Portion 64 has an internally threaded opening therethrough mounting a threaded contact member 69. A resilient blade 70 is secured to and forms an extension of portion 65. The free end of resilient blade 70 car-

ries an electrical contact 72 coactingly opposing member 61 on movable bar 58.

Referring now to Figs. 1 and 7, a U-shaped bracket is secured, as by screws 75, to the interior top wall of casing 10 with its legs 73 and 74 depended therefrom and provided with aligned holes rotatably supporting a hollow shaft 76. The end of shaft 76 extending through leg 73 is internally splined as indicated at 77 to receive the adjacent complementary splined end of the shaft 78 (shown in Fig. 7). Rigidly fastened to the rear portion of shaft 76 (as viewed in Figs. 1 to 4, 7 and 8) is a ratchet wheel 79, and loosely supported on the shaft 76 adjacent the ratchet wheel 79 is an arm 81 having three steps or notches, 82, 83, and 84 on the under or lower side thereof. Fastened to arm 81 in any suitable manner is a plate 85 having two resilient arms 87 and 88 extending therefrom, the free ends of which are adapted to frictionally engage the notched periphery of ratchet wheel 79 so that rotation of the shaft 76 will effect an angular movement of the arm 81 as long as such movement is unimpeded. A limit pin 89 is rigidly fastened to and extends rearwardly from leg 73 into the path of resilient arm 86. After the ratchet wheel 79 and arm 81 have moved a short distance counter-clockwise (see Fig. 1) resilient arm 88 engages pin 89 and is lifted thereby out of frictional engagement with the ratchet wheel 79, thus stopping the movement of the arm 81, although shaft 76 and ratchet wheel 79 continue to turn. A clockwise rotation of the shaft 76 (see Fig. 3) operates through the frictional engagement of the resilient arms 87 and 88 with the ratchet wheel 79 to move arm 81 in clockwise direction until it engages the end of bar 58. When in this position, resilient arms 87 and 88 will then slip over the notched periphery of ratchet wheel 79, permitting shaft 76 to continue turning in clockwise direction.

Plate 13 has a portion cut away to expose a portion of the inner side of the front wall of casing 10 directly behind, to the left of, and beneath bracket leg 74. A conventional relay 91, including an actuating coil enclosed in a casing 92, is secured to that inner side portion of the front wall of casing 10 which is exposed generally beneath bracket leg 74. Relay 91 also includes a movable armature 93 pivoted on resilient spring hinges 94 which are secured to casing 92 in any suitable manner and extend between similar outwardly bent ears 95 on armature 93 and a clamping piece 97, being secured therebetween by screws 98. An irregularly shaped block 99 of insulating material is provided with upturned edges and is secured to the armature 93 by means of screws 100. An L-shaped contact carrying arm 101 is mounted on the block 99 by means of screws 102 and carries at its free end two contacts 103 and 104 adapted to bridge, when the relay coil is energized, threaded contact members 69 and 61, respectively, as shown in Fig. 2. Mounted on the armature 93 by screws or other means is a bracket 106 provided with an offset ear extending generally toward arm 81 and provided at its free end with an internally threaded hole therethrough mounting a screw 107. An upwardly bent member 108 is secured in any suitable manner to the underside of the arm 81 and extends in overlying relation with respect to the screw 107. Relay casing 92 is provided with an off-set arm portion 109 which is disposed in spaced generally parallel relation with respect to armature 93 and mounts a permanent magnet 111

acting to move armature 93 toward same. A conventional transformer 112 is bolted or otherwise secured to that exposed inner wall surface portion of casing 10 just to the left of bracket leg 74 and has primary winding and secondary winding leads connected to elements within the casing as will be explained subsequently.

Referring now to Figs. 9 and 10, a bar 113 of electrical insulating material is secured to the bracket 106 by means of a resilient spring hinge 114, the spring hinge being secured to the bar 113 and bracket 106 by any suitable means. The free end of the bar 113 has fastened thereto an L-shaped latch element 115 which is adapted to engage the free end of the bar 58 (see Fig. 9) under certain conditions. A push button or thrust pin 117 extends through a supporting collar 118, through a front cover 119, through a sleeve 122, through the front wall of the casing 10 but not through plate 13, and through aligned holes in an essentially U-shaped bracket 121 mounted by any suitable means to the exposed inner wall surface of casing 10 generally below bracket leg 74 and above relay casing 92. A compression spring 120 surrounds thrust pin 117 and is disposed between a shoulder 125 thereon and the upper or inner leg of U-shaped bracket 121. A slightly bowed resilient strip 123 is riveted at one of its ends to an extending portion 124 of the bracket 121 and has its free end abutting the bar 113. Spring 120 resists an inward movement of pin 117 and it will be evident from the foregoing that when the pin 117 is disposed as shown in Fig. 10 the resilient strip 123 is forced against the bar 113, causing the spring hinge 114 to flex and the latch 115 to move out of engagement with the free end of the bar 58.

Referring now to Figs. 5 and 7, the casing 10 is mounted by means of lugs 11 and screws 126 on a base plate 127 which in turn is mounted on a plate 128 with spacers 130 interposed therebetween. A tube 131 is secured in any suitable manner to the rear face of the plate 128 and extends rearwardly therefrom in surrounding relation to the shaft 78. Rigidly attached to an extension of the tube 131 is one end of a helical element 132 responsive to changes in temperature of the furnace combustion chamber and adapted to be inserted therein when the control device is properly mounted adjacent the furnace combustion chamber. The other end of the helical element 132 is rigidly secured by any suitable means to the exposed end of shaft 78. It will be evident from the foregoing that a change in combustion chamber temperature will cause the helical element 132 to expand or contract, this expansion or contraction being transmitted to the shaft 78 and causing rotation thereof counter-clockwise upon expansion or heat increase, and clockwise upon contraction or heat decrease, as viewed in Figs. 5 and 6.

The insulating plate 13 (see Fig. 5) is secured to the inner surface of the front wall of casing 10 by means of screws 134, the front wall of the casing having openings 135, 136, and 137 cut therein (of which openings 135 and 137 expose portions of plate 13), and having a depressed portion 138 in which is disposed a relay mounting nut 139 and lock washer 140. The transformer 112 extends partially through the opening 136. The opening 137 allows access to terminals 142 and 143 mounted on plate 13. The base plate 127 is provided with a forwardly extending portion 144 having openings 145 therein permitting

entry of electrical wiring to be connected to the terminals 142, 143, 145, 147, 148, and 149.

Referring now to Fig. 6, the front cover 119 slides over the casing 103 and the forwardly extending portion 144 of the base plate 127 and has an indented portion 150 within which suitable identifying marking may be inscribed. The thrust pin 117 extends through the front cover 119 and through the supporting washer 118 rigidly fastened thereto.

Referring now to Figs. 1, 5, and 11, the high voltage circuit may be connected as follows: One side of a source of electrical current is connected by an external lead to the terminal 148, current may then flow through terminal 148, conductor 67, mounting plate 62, contacts 61 and 72, conductor 201, the transformer primary winding 202 (Fig. 11), conductor 203, the relay coil 204 (Fig. 11), conductor 205, to terminal 147, and then back to the electrical current source. The secondary low voltage circuit may be traced as follows: The transformer secondary winding 206 (Fig. 11), conductor 207, terminal 142, an external connection is made from terminal 142 through a room thermostat 208 of conventional type (Fig. 11) and back to terminal 143, from terminal 143, through conductor 209, heating element 35, and through conductor 210 back to the transformer secondary winding 206 (Fig. 11).

Since terminal 148 is connected to the line source of electrical current, the burner motor circuit can be traced as follows: Terminal 148, conductor 67, relay contacts 69 and 103, relay contacts 104 and 51, conductor 50, terminal 149 (Fig. 5), and from terminal 149 an external connection may be made to the burner motor 211 (Fig. 11) and then back to the line source of electrical current. The igniter circuit may be traced as follows: Terminal 148, conductor 67, relay contacts 69, 103, 104, and 51, bracket 41, contacts 46 and 38, temperature responsive member 26, conductor 212, terminal 146, and from terminal 146 an external connection may be made to the igniter 213 (Fig. 11) and then back to the electrical current source.

The operation of the control device will now be more fully explained. Referring to Fig. 1, the elements of the control device are shown in the position assumed when the room thermostat is satisfied and both the burner and igniter are off. When these conditions exist, (see also Fig. 11), the igniter contacts 38 and 46 and the safety switch contacts 61 and 72 are closed. However, relay coil 204 remains deenergized since the transformer 112 is of the "choke" type, allowing current sufficient to energize the relay to pass through its primary winding 202 only when its secondary circuit is closed. With the room thermostat 208 satisfied, the secondary circuit is open, relay 91 remains deenergized, and relay contacts 103, 69 and 104, 51 remain open. Consequently, the burner and igniter remain deenergized and latch 115 is positioned in the path of bar 58. Helical element 132 (Fig. 7) has cooled since the preceding burner operation and has therefore rotated shaft 78 and ratchet wheel 79 counter-clockwise, which in turn has lifted arm 81 out of engagement with the free end of bar 58.

As the space adjacent the room thermostat cools to a temperature below a predetermined value, the room thermostat closes, completing the transformer secondary circuit through the heating element 35. With the transformer secondary circuit closed, relay 91 is energized, pivoting the armature 93 about its spring hinges 94, which

closes contacts 103, 69 and 104, 51, thereby completing the burner and igniter circuits to establish combustion, at the same time moving latch 115 out of the path of bar 58. It will be noted that the burner and igniter start simultaneously since the relay 91 controls both the burner motor and igniter circuits. If combustion is established the temperature rises, causing helical element 132 to expand and rotate shaft 78 counter-clockwise, lowering arm 81 sufficiently to position its notched portion 82 in the path of the free end of bar 58. The heating capacity of element 35 is so chosen that after a short time, for example 1½ minutes, the temperature responsive element 26 has expanded sufficiently to move contact 38 away from contact 46, thereby breaking the circuit to the igniter 213. It may thus be seen that the igniter remains energized a period of time dependent on the heating capacity of heater 35. Magnet 48 causes contacts 38 and 46 to separate with a snap action in a conventional known manner. Since arm 81 is positioned so that its notch 82 may be engaged by the free end of bar 58, the expansion of temperature responsive element 26 does not move the bar 58 sufficiently to open safety switch contacts 61 and 72; such action moves the free end of bar 58 into engagement with notch 82 of arm 81, whereupon the continued movement of element 26 merely moves pin 40 through the opening in bar 58 thereby compressing spring 60. Consequently relay 91 remains energized, thus holding its contacts 103 and 104 in bridging engagement with contacts 69 and 51. With relay contacts 103, 69 and 104, 51 closed and igniter switch contacts 38 and 46 open, the furnace is in normal operation and the elements of the control device assume the positions shown in Fig. 2.

After the room thermostat closes and the relay 91 is energized, an electrical circuit is completed to the burner and igniter. If the igniter fails and combustion is not initially established, arm 81 will remain out of engagement with the free end of bar 58. After the heating element 35 has heated member 26 the ignition contacts 38 and 46 and safety switch contacts 61 and 72 will be opened with a snap action. When contacts 61 and 72 are opened, relay 91 is deenergized, stopping the burner. The above mentioned snap action and the resilient effect of the blade 10 causes the free end of the bar 58 to move to the left (as viewed in Fig. 1) before movement of relay 91 to deenergized position is completed; consequently, latch 115 holds the free end of bar 58 (see Fig. 11) and prevents cooling of member 26 from again closing contacts 61 and 72 and recycling the control device. Thus upon initial failure of combustion the control device will not recycle, but will assume safety shut down position.

If during normal burner operation a flame failure should occur, the combustion chamber temperature will begin to decrease and shaft 76 will be rotated counter-clockwise, lifting arm 81 out of engagement with the free end of bar 58, at the notch 82. As soon as this occurs, spring 60, which was placed under considerable compression by the heater actuated movement of member 26, will force the free end of bar 58 into engagement with notched portion 83 of arm 81, such further movement of bar 58 being sufficient to open safety switch contacts 61 and 72 (see Fig. 3). When safety switch contacts 61 and 72 are open, the transformer primary circuit is broken and the relay 91 is deenergized, thus breaking the burner motor circuit through the opening of contacts 103,

69, and 104, 51. The deenergization of relay 91 also positions latch 115 in the path of the free end of bar 58, thus preventing any further movement of same toward notched portion 84 of arm 81. In addition, heating element 35 is deenergized and begins to cool. In this connection it should be noted that in Fig. 3 the elements of the control device are shown in the positions assumed just after the safety switch contacts 61 and 72 have opened and relay contacts 103, 69 and 104, 51 are about to open.

As the heating element 35 cools, the temperature responsive member 26 moves the igniter contact 38 back into engagement with contact 46 and through pin 40 moves safety switch contact 61 back into engagement with contact 72. Assuming that the room thermostat is still calling for heat and the transformer secondary circuit is therefore closed, relay 91 will be immediately energized, thus closing contacts 103, 69 and 104, 51, thereby closing the burner motor and igniter circuits. If conditions causing the flame failure have been removed, the burner motor and igniter will proceed through a normal heating cycle and arm 81 will move into engagement with bar 58 as described previously with reference to Fig. 1. However, if combustion does not occur upon reclosing of the burner motor and igniter circuits, the furnace combustion chamber will continue to cool and arm 81 will move to its extreme counter-clockwise position (see Fig. 4). The burner motor and igniter will operate until heating element 35 causes temperature responsive element 26 to open igniter contacts 38 and 46, and since arm 81 is in its extreme counter-clockwise position, as seen in Figure 4, the temperature responsive element 26 will move bar 58 into engagement with the arm 81 at notch 84 and will open the safety switch contacts 61 and 72. Opening contacts 61 and 72 breaks the transformer primary circuit and deenergizes relay 91. As the relay armature 93 moves to its deenergized position it opens relay contacts 103, 69 and 104, 51, stopping the burner, and also moves the latch 115 into a retaining engagement with bar 58 thereby holding it in a position preventing reclosure of the safety switch contacts 61 and 72 as the heating element 35 cools and igniter contacts 38 and 46 again close. With safety switch contacts 61 and 72 and relay contacts 103, 69 and 104, 51 all open, both the burner and igniter circuits are open, the elements of the control device assuming the positions shown in Fig. 4. The burner and igniter are now inoperative and the control device is in safety shut-down position.

To restart the burner and igniter the manual reset mechanism must be actuated. Referring now to Fig. 9, in which bar 113 and latch 115 are positioned as shown in Fig. 4, if thrust pin 117 is manually depressed its inner end will engage the bowed resilient member 123, causing it to flex against the bar 113 pivoting the bar 113 and latch 115 out of engagement with contact carrying bar 58 (see Fig. 10). This allows the safety switch contacts 61 and 72 to close and the burner and igniter to thereupon begin a normal cycle establishing combustion, as previously described with reference to Fig. 1. If the thrust pin 117 were tied down in the actuated position by an inexperienced furnace attendant and relay 91 could be energized while the pin 117 was so held in actuated position, the safety shut down latch 115 would be ineffective to prevent repeated recycling and consequent building up of a dangerous concentration of unburned fuel, since the latch 115

would remain out of engagement with contact carrying bar 58. This danger is removed by preventing armature 93 from moving and closing relay contacts 103, 69 and 104, 51 as long as the thrust pin 117 is in actuated position. Referring to Fig. 9, when the relay 91 is energized, armature 93 is pulled downwardly and the bar 113 thereupon depresses the free end of resilient member 123 slightly. With pin 117 in its actuated position, engaging resilient member 123 (see Fig. 10), the effective length of the resilient member is reduced and a much greater force is necessary to depress its free end an amount sufficient to allow armature 93 to move to relay energized position. Relay 91 is incapable of supplying this greater force and consequently armature 93 will not move to close relay contacts 103, 69 and 104, 51 as long as pin 117 is engaging resilient member 123, and thus the burner and igniter remain inoperative until pin 117 is released. Moreover, accidental bumping of the reset button while the burner is in operation will not result in the relay armature moving to deenergized position and shutting down the burner, since the force resulting from depressing thrust pin 117, while sufficient to keep armature 93 from moving to relay energizing position, is insufficient to move armature 93 to its deenergized position so long as the relay 91 remains energized.

Screw 107 engages the underside of the upwardly bent member 108 on the arm 81 each time armature 93 moves to its deenergized position, such movement of screw 107 being effective to move arm 81 counter-clockwise to the position shown in Fig. 4, that is, away from and out of engagement with the free end of bar 58. This coaction between screw 107 and member 108 affords still another safety feature in that should the combustion responsive device fail to operate on cooling, arm 81 will not remain in engagement with the free end of bar 58, to render the safety shut down latch 115 ineffective. Magnet 111 is provided for the purpose of pulling armature 93 into its deenergized position with sufficient force to effect the movement of arm 81 just described.

Ambient temperature compensation or compensation for fluctuations of the temperature of the space surrounding the control device is provided by the rear temperature responsive member 27 (see Fig. 1). A change in ambient temperature, for example an increase in ambient temperature, will tend to move leg 28 of member 26 to the left (as viewed in Fig. 1). The increase in ambient temperature will also tend to move leg 31 of member 27 to the left. However, spring 21 is strong enough to hold leg 31 against the stop 19. Consequently, leg 30 will move to the right (as viewed in Fig. 1). This movement to the right of leg 30 will be transmitted to legs 28 and 29 of member 26, since legs 29 and 30 of members 26 and 27 respectively are fastened together by plate 23. Leg 28 of member 26 will consequently be held in substantially the same position relative to fixed contacts 46 at any ordinary ambient temperature.

In addition to affording the safety features hereinabove pointed out in connection with the described mode of operation, a construction and combination of parts conforming with the present invention affords a durable and compact mechanism for safely and efficiently effecting the timed ignition and recycling operation with but a few simple control elements which can be readily manufactured at a competitive cost and

assembled and calibrated with a minimum of time, effort, and skill.

Moreover, it should be apparent that certain of the features of construction and certain of the combinations of parts herein disclosed are in general applicable to combustion control devices of all types, and that apparatus embodying the invention may vary considerably from that herein shown and described for purposes of illustration. It should therefore be understood that it is not intended to limit the invention to the exact construction and/or combinations of elements shown and described herein, as various modifications within the scope of the appended claims may occur to persons skilled in the art.

What is claimed is:

1. In a control system for a fuel burning heating apparatus including, in circuit with a power source, a means automatically positioned to initiate combustion in response to a demand for heat and to terminate combustion when the demand for heat is satisfied and including a normally closed safety switch controlling said means, means for opening said safety switch including a movable thermally operated member, means including a combustion controlled element positionable as the result of combustion to arrest a switch opening movement of said member, said combustion initiating and terminating means including a part positioned to limit the switch opening movement of said member in the event such movement is arrested by said combustion controlled element and to engage and retain said member in a position holding said safety switch open in the event the switch opening movement of said member is not arrested by said combustion controlled element, a heater operatively associated with said thermally operated movable member, and control circuit means for said combustion heater and initiating and terminating means dominated by said safety switch.

2. In a control system for a fuel burning device including fuel feeding and ignition means, mechanism for controlling said means comprising, in circuit with a power source, means including a relay controlled switch positionable to initiate combustion in response to a demand for heat and to terminate combustion when the demand for heat is satisfied, means including a normally closed safety switch controlling energization of said relay, means for opening said safety switch including a thermally operated movable member, means including a combustion controlled element positionable as the result of combustion to arrest a switch opening movement of said member, a part positioned by said relay to limit the switch opening movement of said member in the event such movement is arrested by said combustion controlled element and to engage and retain said member in a position holding said safety switch open in the event the switch opening movement of said member is not arrested by the combustion controlled element, a heater operatively associated with said thermally operated movable member, and control circuit means for said relay and heater dominated by said safety switch.

3. In a control system for a fuel burning heating apparatus including circuit connections with a power source, a first means in said circuit automatically positioned to initiate combustion in response to a demand for heat and to terminate combustion when the demand for heat is satisfied and including a normally closed safety switch

controlling said means, a second means for opening said safety switch including a movable thermally operated member, means including a combustion controlled element positionable as a result of combustion to arrest a switch opening movement of said member, said first means including a part movable therewith into and out of the path of movement of said member to limit the switch opening movement of said member in the event such movement is arrested by said combustion controlled element and to engage and retain said member in a position holding said safety switch open in the event the switch opening movement of said member is not arrested by said combustion controlled element, a heater operatively associated with said thermally operated movable member, control circuit means for said heater and said first means, a reset member manually actuatable to release said first means part from latching engagement with said movable member, and an additional part operated with said reset member constructed and arranged to render the first means incapable of initiating combustion when the reset member is held in latch releasing position.

4. In a control system for a fuel burning device including fuel feeding and ignition means, control means for controlling said means including, circuit connections with a power source, a relay controlled switch positionable to initiate combustion in response to a demand for heat and to terminate combustion when the demand for heat is satisfied, a normally closed safety switch controlling energization of said relay, means for opening said safety switch including a thermally operated movable member, means including a combustion controlled element positionable as the result of combustion to arrest a switch opening movement of said member, a part positioned by said relay to limit the switch opening movement of said member in the event such movement is arrested by said combustion controlled element and to engage and retain said member in a position holding said safety switch open in the event the switch opening movement of said member is not arrested by the combustion controlled element, a heater operatively associated with said thermally operated movable member, control circuit means for said relay and heater dominated by said safety switch, a reset member manually actuatable to release said part from latching engagement with said movable member, and means including an additional part associated with said relay positioned part and reset member in a manner such that so long as said reset member is held in its latch releasing position said relay is incapable of positioning said relay controlled switch to initiate combustion.

5. In a control system for a fuel burning device including fuel feeding and ignition means, mechanism for controlling said means including, in circuit with a power source, a relay controlled switch positionable to initiate combustion in response to a demand for heat and to terminate combustion when the demand for heat is satisfied, an ignition switch controlling said ignition means, a safety switch, a movable member arranged to operate said safety switch, thermal warp element means arranged to operate said ignition switch and actuate said movable member, said warp element means being movable sufficiently when heated to open said ignition switch and to effect a safety switch opening movement of said member, a combustion responsive device including an element positioned as a result

of combustion to establish a relationship with said movable member such that said safety switch remains closed while said warp element means is heated and moves sufficiently to open said ignition switch, a part controlled by said relay for movement into a position permitting only a limited further switch opening movement of said member in the event of a power failure, a heater operatively associated with said warp element means, and a control circuit means for said relay and heater dominated by said safety switch.

6. In a control system for a fuel burning device including fuel feeding and ignition means, mechanism for controlling said means including, in circuit with a power source, a relay controlled switch positionable to initiate combustion in response to a demand for heat and to terminate combustion when the demand for heat is satisfied, an ignition switch controlling said ignition means, a safety switch, a movable member arranged to operate said safety switch, thermal warp element means arranged to operate said ignition switch and actuate said movable member, said warp element means being movable sufficiently when heated to open said ignition switch and to effect a safety switch opening movement of said member, a combustion responsive device including a stepped element positioned as a result of combustion to act as a stop for said movable member such that said safety switch remains closed while said warp element means is heated and moves sufficiently to open said ignition switch, said stepped element being constructed and controlled in a manner such that upon a failure of combustion said element is moved relative to said member first to an intermediate position which presents another step which permits switch opening movement of said member and then to a final position which permits continued movement of said member, a part controlled by said relay for movement into a position permitting only a limited further switch opening movement of said member in the event of combustion failure and a resulting movement of said element to said final position, a heater operatively associated with said warp element means, and control circuit means for said heater and relay dominated by said safety switch.

7. In a control system for a fuel burning device including fuel feeding and ignition means, mechanism for controlling said means including, in circuit with a power source, a relay controlled switch positionable to initiate combustion in response to a demand for heat and to terminate combustion when the demand for heat is satisfied, and ignition switch controlling said ignition means, a safety switch, a movable member arranged to operate said safety switch, thermal warp element means arranged to operate said ignition switch and actuate said movable member, said warp element means being movable sufficiently when heated to open said ignition switch and to effect a safety switch opening movement of said member, a combustion responsive device, a stop element having a lost motion connection with said device and positioned thereby as a result of combustion to arrest movement of said movable member so that said safety switch remains closed while said warp element is heated and moves sufficiently to open said ignition switch, a first means controlled by said relay for movement into a position permitting only a limited further switch opening movement of said member in the event of a power failure,

a second means controlled by said relay and including a projection engageable with a portion of said stop element to positively move the latter to a position removing the stop between said device and member whenever said relay is deenergized, a heater operatively associated with said warp element means, and control circuit means for said relay and heater dominated by said safety switch.

- 10 8. In a control system for a fuel burning device including fuel feeding and ignition means, mechanism for controlling said means including, in circuit with a power source, a relay controlled switch positionable to initiate combustion in response to a demand for heat and to terminate combustion when the demand for heat is satisfied, an ignition switch controlling said ignition means, a safety switch, a movable member arranged to operate said safety switch, thermal warp element means arranged to operate said ignition switch and actuate said movable member, said warp element means being movable sufficiently when heated to open said ignition switch and to effect a safety switch opening movement of said member, a combustion responsive device including an element positionable as a result of combustion to engage said movable member and establish a relation therewith such that said safety switch remains closed while said warp element means is heated and moves sufficiently to open said ignition switch, said combustion device element being held out of engagement with said movable member in the event combustion is not initiated, a part mechanically connected with said relay for movement into a position retainably engaging said member in response to the latter moving sufficiently to open said safety switch as a result of failure to initiate combustion, a heater operatively associated with said warp element means, and control circuit means for said relay and heater dominated by said safety switch.

- 45 9. In a control system for a fuel burning device including fuel feeding and ignition means, mechanism and circuits for controlling said means including, in circuit with a power source, a relay controlled switch positionable to initiate combustion in response to a demand for heat and to terminate combustion when the demand for heat is satisfied, an ignition switch in the circuit for said ignition means and disposed in controlled relation with respect to said relay switch, a safety switch arranged to control said relay, a movably mounted member for operating said safety switch, thermal warp element means arranged to operate said ignition switch and actuate said movably mounted member, said warp element means being movable sufficiently when heated to open said ignition switch and to effect a safety switch opening movement of said member, a combustion responsive device including an element positionable as a result of combustion to engage said movable member and establish a relationship with said device and movable member such that said safety switch remains closed while said warp element is heated and moves sufficiently to open said ignition switch, said combustion device element being normally held out of engagement with said movable member in the event combustion is not initiated and being provided with stop steps positioned relative to said member to permit a further step-by-step switch opening movement of the latter, a part connected with said relay for movement into a position permitting only a limited further switch

opening movement of said member in the event of combustion failure and a resulting movement of said element to terminate said relationship between said device and member, said part being constructed and arranged retainably to engage said member in the event the latter opens said safety switch upon failure to initiate combustion, a heater operatively associated with said warp element means, and control circuit means for said relay and heater dominated by said safety switch.

10. In a control system for a fuel burning heating apparatus including in circuit with a power source, a first means automatically positioned to initiate combustion in response to a demand for heat and to terminate combustion when the demand for heat is satisfied, a safety switch controlling said means, a second means for opening said safety switch including a movable member and a thermal warp element having a lost motion actuating connection with said member, a combustion controlled element positionable as the result of combustion to arrest a switch opening movement of said member, said first means including a part movable therewith and positioned to limit the switch opening movement of said member in the event such movement is arrested by said combustion controlled element and to engage and retain said member in a position holding said safety switch open in the event the switch opening movement of said member is not arrested by said combustion controlled element, a heater operatively associated with said warp element, control circuit means for said first means and heater dominated by said safety switch, a reset mechanism for releasing said first means part from latching engagement with said movable member, said reset mechanism comprising a manually movable thrust pin, a resilient lever arranged to oppose movement of the first means, said thrust pin being arranged to engage said resilient lever upon manual actuation of said resetting mechanism thereby changing the effectiveness of said resilient lever in opposing movement of said first means and rendering said first means incapable of being positioned to initiate combustion so long as said reset mechanism is held in actuated position.

11. In a control for fuel burning heating apparatus, the combination of, control means adapted to control said apparatus, said control means being constructed and arranged to provide a normal relationship between its parts which permits normal operation of said apparatus, and to provide a safety relationship between its parts which prevents operation of said apparatus, means responsive to presence or absence of combustion in said apparatus for controlling said control means, said responsive means being constructed and arranged to cause the control means to assume its safety relationship of parts upon failure of combustion, reset means for returning the control means from its safety relationship of parts to its normal relationship of parts, said reset means including a reset element having a normal position but movable therefrom to engage parts of said control means for returning the same to its normal relationship of parts, and mechanical means associated with said reset means for mechanically engaging parts of said control means, said mechanical means being constructed and arranged to mechanically disable said control means from permitting normal operation of said

apparatus when the reset element is away from its normal position.

12. In a control for fuel burning heating apparatus, the combination of main control means adapted to start and stop said apparatus in response to demand for heat, safety means having a first position which permits operation of said apparatus by the main control means and having a second position which prevents operation of said apparatus by the main control means, combustion responsive means arranged to cause said safety means to assume its second position upon failure of combustion to take place, manual reset means for returning the safety means to its first position, said manual reset means including a reset element having a normal position but movable therefrom to engage said safety means to return it to its normal position, a device for mechanically blocking said main control means in a manner to prevent it from starting said apparatus, and means for conditioning said device for blocking action when the reset element is moved away from its normal position.

13. In a control for fuel burning heating apparatus, the combination of, a relay adapted to start and stop said apparatus, a safety switch having a first position which permits the relay to start the apparatus and a second position which prevents the relay from starting the apparatus, means including combustion responsive means arranged to cause the safety switch to assume its second position upon failure of combustion to take place, means for causing said safety switch to remain in such position until manually reset, a manual reset element having a normal position but movable therefrom to reset said safety switch, a device for mechanically blocking the relay to prevent it from starting the heating apparatus, and means for conditioning said device for blocking action when the reset element is moved away from its normal position.

14. In a safety control adapted to control a power operated device, the combination of, control means adapted to control said power operated device, said control means being constructed and arranged to have a normal relationship between its parts for permitting normal operation of said power operated device and a safety relationship preventing normal operation of said power operated device, responsive means adapted to respond to an operating condition for said power operated device for controlling said control means, said responsive means being constructed and arranged to cause said control means to assume its safety relationship upon the occurrence of an improper operating condition for said power operated device, reset means for returning the control means from its safety relationship to its normal relationship, said reset means including a reset element biased in one direction but movable in another direction against its bias to engage parts of said control means for returning the same to its normal relationship, and mechanical means associated with said reset means for mechanically engaging parts of said control means, said mechanical means being constructed and arranged to mechanically disable said control means from permitting normal operations of said power operated means when the reset element is in position to return the control device to its normal relationship.

15. In a control system for a fuel burning heating apparatus, main control means adapted to start and stop said apparatus, means including a safety switch also in control of said apparatus

and arranged when in a first position to permit operation of said apparatus and when in a second position to prevent operation of said apparatus by said main control means, means including timing means tending to cause movement of the safety switch to its second position a period of time after starting of said apparatus by said main control means, combustion responsive means acting on presence of combustion to prevent opening of said safety switch by action of said timing means, and abutment means operated with said main control means, said abutment means being movable independently of said combustion responsive means into one position limiting safety switch opening movement by said timing means and into another position preventing reclosing of said safety switch.

16. In a control system for fuel burning heating apparatus, main control means adapted to start and stop said apparatus, means including timing means and combustion responsive means for stopping said apparatus automatically if combustion fails to occur, said last mentioned means including a member responsive to combustion and an element movable by said member from a "cold" position to a "hot" position when combustion occurs, and means independent of said member responsive to combustion and independent of said timing means for returning said element from its "hot" position to its "cold" position when the burner is stopped by said main control means.

17. In a control system for fuel burning heating apparatus, main control means adapted to start and stop said apparatus, means including timing means and combustion responsive means for stopping said apparatus automatically if combustion fails to occur, said last mentioned means including a member responsive to combustion and an element movable by said member from a "cold" position to a "hot" position when combustion occurs, and means independent of said member responsive to combustion and independent of said timing means for returning said element from its "hot" position to its "cold" position when the burner is stopped by said main control means.

18. In a control system for fuel burning heating apparatus, a relay adapted to start and stop said apparatus, means including timing means and combustion responsive means for stopping said apparatus automatically if combustion fails to occur, said last mentioned means including a member responsive to combustion and an element movable by said member from a "cold" position to a "hot" position when combustion occurs, and means, independent of said member responsive to combustion and independent of said timing means, actuated by said relay for urging said element toward its cold position when the relay stops said heating apparatus.

19. In a control system for fuel burning heating apparatus, a main control means for starting and stopping said apparatus, means including secondary control means having a starting position which permits said main control means to start the apparatus and a safety position which prevents the main control means from starting the apparatus, timing means associated with said secondary control means and tending to move the same from its starting position to its safety position a period of time after the apparatus is started by said main control means, combustion responsive means, an element operated between "hot" and "cold" positions by said combustion responsive means and in its hot position mechanically arresting the action of said timing means,

and means independent of said combustion responsive means and of said timing means for returning said element from its "hot" position to its "cold" position when the apparatus is stopped.

20. In a control system for a fuel burning device including fuel feeding and ignition means, mechanism for controlling said means including, in circuit with a power source, a relay controlled switch positionable to initiate combustion in response to a demand for heat and to terminate combustion when the demand for heat is satisfied, an ignition switch controlling said ignition means, a safety switch, a movable member arranged to operate said safety switch, thermal warp element means arranged to operate said ignition switch and actuate said movable member, said warp element means being movable sufficiently when heated to open said ignition switch and to effect a safety switch opening movement of said member, a combustion responsive device, a stop element having a lost motion connection with said device and positioned thereby as a result of combustion to arrest movement of said movable member so that said safety switch remains closed while said warp element is heated and moves sufficiently to open said ignition switch, said stop element being constructed and controlled in a manner such that upon a failure of combustion such element is moved relative to said member to permit a further step-by-step switch opening movement of the latter, a first means controlled by said relay for movement into a position permitting only a limited further switch opening movement of said member in the event of a power failure, second means controlled by the relay and including a projection engageable with a portion of said stop element to positively move the latter to a position terminating the connection between said device and member whenever said relay is de-energized, a heater operatively associated with said warp element means, and a control circuit means for said relay and heater dominated by said safety switch.

21. In a control system for a fuel burning apparatus including, in circuit with a power source, a means automatically positioned to initiate combustion in response to a demand for heat and to terminate combustion when the demand for heat is satisfied and including a normally closed safety switch controlling said means, means for opening said safety switch including a hinged member and a thermal warp member, a lost motion connection between said members, said lost motion connection comprising a pin pivotally mounted on one of said members and slidably connected to the other of said members and also including a spring interposed between said members for biasing them apart, a combustion responsive device, means including an element having a lost motion connection with said device and positioned thereby as a result of combustion to engage said hinged member and obstruct the movement thereof.

22. In a control for fuel burning heating apparatus, the combination of, control means adapted to control said apparatus, said control means including a latching member and a movable member and being constructed and arranged to provide a normal relationship between said latching member and said movable member which permits normal operation of said apparatus, and to provide a safety latching relationship between said latching member and said movable member, means responsive to presence or absence of combustion in said apparatus for controlling said

control means, said responsive means being constructed and arranged to cause the control means to assume its said safety latching relationship of parts upon failure of combustion, reset means for returning the control means from its said safety latching relationship of parts to its said normal relationship of parts, said reset means including a reset member manually actuatable to release said movable member from latching relationship with said latching member, and means including an additional resilient part operatively associated with said latching member and said reset member in a manner such that so long as said reset member is held in latch releasing position said control means is mechanically disabled from permitting normal operation of said apparatus.

Certificate of Correction

Patent No. 2,521,717

September 12, 1950

JOHN L. HARRIS

It is hereby certified that error appears in the printed specification of the above numbered patent requiring correction as follows:

Column 4, line 38, for "strip 46" read *strip 36*; column 11, line 40, for the words "combustion heater and" read *heater and combustion*; column 13, line 57, for "and ignition" read *an ignition*;

and that the said Letters Patent should be read as corrected above, so that the same may conform to the record of the case in the Patent Office.

Signed and sealed this 5th day of December, A. D. 1950.
